(57) **CLAIM**

The ornamental design for an inducer impeller, as shown and described.

DESCRIPTION

FIG. 1 is a first perspective view of an inducer impeller, taken from above.

FIG. 2 is a second perspective view of the inducer impeller, taken from below.

FIG. 3 is a front view of the inducer impeller of FIG. 1.

FIG. 4 is a back view of the inducer impeller of FIG. 1.

FIG. 5 is a left-side view of the inducer impeller of FIG. 1.

FIG. 6 is a right-side view of the inducer impeller of FIG. 1.

FIG. 7 is a top view of the inducer impeller of FIG. 1.

FIG. 8 is a bottom view of the inducer impeller of FIG. 1.

FIG. 9 is a cross-sectional view of the inducer impeller taken along line 9-9 shown in FIG. 7 ; and,

FIG. 10 is a cross-sectional view of the inducer impeller taken along line 10-10 shown in FIG. 7 .

The broken lines represent features of the inducer impeller which form no part of the claimed design.
